INVENTOR

ATTORNEY

UNITED STATES PATENT OFFICE.

ALONZO E. DECKER, OF FREMONT, OHIO, ASSIGNOR OF ONE-HALF TO FRANK P. SMITH,
OF FREMONT, OHIO.

WEATHER STRIP.

Application filed December 29, 1924. Serial No. 758,769.

To all whom it may concern:

Be it known that I, ALONZO E. DECKER, a citizen of the United States, residing at Fremont, in the county of Sandusky and State of Ohio, have invented new and useful Improvements in Weather Strips; of which the following is a specification.

This invention relates to weather strips for doors and has for its object the provision 10 of a novel weather strip designed to be hingedly mounted at the lower edge of a door and adapted to be operated whereby to engage against the door sill automatically when the door is closed for excluding draft.

15 An important and more specific object is the provision of a weather-strip device of this character in which the strip may be either recessed into the door or mounted upon the side thereof, without recessing, the strip being normally spring pressed into inoperative or non-obstructing position and co-operating with an automatic spring pressed trip device whereby it will be positively forced into engagement with the door 25 sill when the door is swung into closed position.

Another object is the provision of a device 30 of this character which will be simple and inexpensive in manufacture, easy to apply or install, automatic in operation, efficient and durable in service, and a general improvement in the art.

With the above and other objects and advantages in view, the invention consists in 35 the details of construction to be hereinafter more fully described and claimed, and illustrated in the accompanying drawings in which:

40 Fig. 1 is a vertical section through a door equipped with my device showing it in open position and showing it ready for engagement with the automatic closing or trip device,

45 Fig. 2 is a similar view showing the door in closed position and the weather strip in engagement with the sill,

Fig. 3 is a detail section through the casing containing the trip mechanism.

50 Referring more particularly to the drawings, the letter A designates a door jamb, B represents the hingedly mounted door and C the sill therefor. The floor is indicated by the letter D.

55 In carrying out the invention, I provide a strip 31 mounted, by means of hinges 32,

upon a strip 33 secured to the door B, the strip 31 being engaged and normally urged upwardly into inoperative position by a spring or springs 34 mounted between the strip 33 and the door.

The door jamb or frame A is provided with a recess 35 within which is located a casing 36 which encloses the trip mechanism which consists of an elongated link 37 which is slidably mounted transversely through the casing 36 and guided by screws or the like 38 which pass through elongated slots 39 in the link. One of the screws 38 also passes through and serves to pivot a trip 40 which is engaged by a pair of leaf springs 41 and 42 mounted in any convenient manner as for example by being inserted within a slot 43. Adjustment of the tension may be obtained by means of a screw 44 which is adapted to engage the springs 42.

In the operation, it is apparent that when the door is open the strip 31 is held elevated by the spring means 34. When the door is closed, the strip 31 will engage against the trip 40 and the latter will exert a camming effect which will swing the strip 31 downwardly against the resistance of the springs 34 until it engages the resilient strip element 17 carried by the sill. During this movement of the strip 31 it is evident that the trip 40 must move rearwardly against the resistance of the springs 41 and 42 so as not to obstruct the weather strip 31. During this movement the link 37 upon which the trip 40 is carried must slide transversely through the door. The movement is well illustrated, and it is consequently believed that further explanation will be unnecessary.

From the foregoing description and a study of the drawings it will be apparent that I have thus provided a simply constructed, inexpensive and easily installed device for the purpose specified which will efficiently perform all the functions for 100 which it is intended and which on account of the fewness of the parts is not likely to get out of order.

While I have shown and described the preferred embodiment of the invention, it 105 should be understood that I reserve the right to make such changes in the form, construction and arrangement of parts as will not depart from the spirit of the invention or the scope of the subjoined claims. 110

Having thus described the invention, I claim:

1. In combination with a door and its jamb, a weather strip hingedly mounted at the lower portion of the door, a leaf spring recessed into the door and of angular shape with a portion bearing against said strip to normally urge it away from the door sill, and a trip mounted on the door jamb and including an elongated slotted member slidably adjustably mounted toward or from the door, and a spring pressed pawl-like member pivoted on said slotted member and disposed in the path of travel of the strip.
- 10 2. In combination with a door and its sill and jamb, a weather strip hinged upon the lower portion of the door, means normally urging said strip upwardly away from the door sill, the jamb being recessed, a horizontally disposed member located within the recess and formed with a longitudinal slot, a cover plate for the recess, a securing element passing through the cover plate and said slot for adjusting said elongated member toward or from the door, a pawl member pivotally mounted on the end of said elongated member nearest the door and positioned in the path of travel of the strip, spring means urging said pawl member toward the door, and means for limiting swinging movement of the pawl member away from the door.

In testimony whereof I affix my signature.

ALONZO E. DECKER.
